UNITED STATES PATENT OFFICE.

FRANK J. MACDONALD, OF AKRON, OHIO, ASSIGNOR TO THE B. F. GOODRICH COMPANY, OF NEW YORK, N. Y., A CORPORATION OF NEW YORK.

METHOD AND APPARATUS FOR MAKING FOOTWEAR.

Application filed September 18, 1924. Serial No. 738,378.

This invention relates to the manufacture of footwear and more particularly to methods and apparatus for incorporating pieces of stock such as heel pieces or counters. While the machine shown in the accompanying drawings is primarily designed for incorporating the piece of stock commonly called the "cloth heel", in the building of rubber footwear, the invention in some of its features is applicable to leather footwear and to shoe parts other than the cloth heel.

My object is to provide improved procedure and improved, largely automatic apparatus, adapted for rapid, accurate and economical production.

Of the accompanying drawings:

Fig. 1 is a front elevation of a machine embodying and adapted to carry out my invention in its preferred form, a part being broken away, and the machine being shown in its initial stage of operation.

Fig. 2 is a side elevation of the same, from the right of Fig. 1.

Fig. 3 is a vertical section of the same, on line 3—3 of Fig. 1.

Fig. 4 is a perspective view of the finished work.

Fig. 5 is a horizontal section on line 5—5 of Fig. 3.

Fig. 6 is a front elevation of parts of the machine at the initial stage of operation, parts being sectioned and broken away.

Fig. 7 is a section on line 7—7 of Fig. 6.

Fig. 8 is a front elevation of the parts of the machine shown in Fig. 6, but at a later stage of operation.

Fig. 9 is a vertical section of part of the machine, taken on line 9—9 of Fig. 8, and showing a still later stage of operation than that of Fig. 8.

General description.

Referring to the drawings, the machine comprises means for receiving and supporting in determinate position and in a flat or spread condition a cloth heel piece 10, preferably disposed horizontally; means adapted to receive a last 11, with inner shoe parts mounted thereon, and to carry the last downward in a determinate course, with its sole disposed substantially in a vertical plane, against the heel piece in such manner as to cause the heel piece to be applied to the

underlying shoe parts progressively, in opposite directions from the middle line of the heel, the heel-piece-supporting means being adapted to maintain a pull upon the ends of the heel piece while relinquishing the support of its middle portion to permit it to be flexed into conformity with the last by movement of the latter; means for folding the sole margin of the heel piece onto the sole face of the last; and means for pressing the folded margin of the heel piece to compact it against the sole face of the last.

It will be understood that the heel piece is applied to the last after other inner shoe parts, such as the lining 12 and the insole 13, Fig. 4, have been applied, and for brevity the word "last" will be used hereinafter as including a last having such parts in place upon it, as well as a bare last.

Last manipulating mechanism.

The machine comprises a base 14 from which rises a pair of standards 15, 16 formed with various mountings including two pairs of vertically spaced-apart brackets 17, 17, 18, 18, in which are secured respective upwardly projecting guide posts 20, 20, for a last-carrying cross-head or slide 21 formed with two pairs of apertured arms 22, 22 and 23, 23, slidably mounted upon said guide posts, respectively above and below the upper frame brackets 17.

Secured to the top of each of the stationary guide-posts 20 is a stop-collar 24 and a pair of journal brackets 25, 25 for a set of grooved pulleys 26, 26, over which a cable 27 passes from an anchorage 28 on the slide 21 to a counterweight 29 provided with a guide pin 29^a sliding in a bracket 29^b formed on the standard 15 or 16 and provided with a stop pad 29^c for the counterweight, the two counterweights being adapted to avoid excessive power requirement in any part of the upward and downward movement of the slide. A pitman 30, for effecting such movement, is provided at its upper end with a cross-pin 31 projecting through vertical slots 32, 32, formed in ears 33, 33 which are integral with the slide 21, the pitman thus having a lost-motion connection with the slide.

The lower end of the pitman 30 is pivoted to a crank 34 secured upon a shaft 35 journaled in a part of the standard 16 and hav-

ing secured on its outer end a mutilated gear 36 having a tooth omitted at opposite sides to permit it to be driven through timed half-revolutions by a mutilated gear 37 formed with two sets of teeth so spaced apart as to permit a substantial dwell of the slide 21 in its lowermost position, and as to be in unmeshed relation, as is clearly shown in Fig. 2, when the gear 37 is stopped between successive full revolutions thereof, so that slight over-running of the gear 37 may not affect the starting position of the pitman 30 and its projecting cross-pin 31, which latter is adapted to actuate certain cam members, hereinafter described, during the take-up of the lost motion between the pitman 30 and the slide 21,

The gear 37 is secured upon a shaft 38 journaled in the standards 15, 16 and having secured thereon a cam drum 39 and a gear 40, the latter being meshed with a gear 41 secured on a hollow shaft 42 journaled in the standard 15 and having secured on its other end a brake drum 43 formed with a jaw-clutch hub 44, the latter being adapted to mate with a jaw-clutch member 45 secured upon a shaft 46 slidably and rotatably mounted in the standard 16 and in the axial aperture of the hollow shaft 42, said shaft 46 being provided with a belt pulley 47 by which it may be continuously driven from a suitable source of power.

A shipper lever 48 for the clutch member 45 is secured upon a shaft 49 provided with a foot lever 50 adapted to act against a pull spring 51 to engage the clutch, and said shipper lever 48 is formed integrally with a brake lever 52 and a brake shoe 53 thereon adapted to act against the brake drum 43, under the force of the spring 51, when the clutch is disengaged, to prevent overrunning of the mechanism.

For holding the clutch engaged through a cycle of operations, unless sooner released by the operator, a latch lever 54 is formed integrally with the shipper lever 48, and a latch 55 (Fig. 3), adapted to hold the shipper lever in clutch-engaging position, is secured to a shaft 56 provided with a foot lever 57 for withdrawing the latch at the will of the operator, said shaft 56 also being provided with a cam-lever 58 adapted to be engaged by a dog 59 on the cam drum 39 at the end of each revolution of the shaft 38, to withdraw the latch, against the force of a pull spring 58^a (Fig. 3) connecting the lever 58 with a part of the machine frame and urging the latch 55 toward its latching position.

The mechanism described is thus adapted, upon being started by depression of the foot lever 50, to lower the slide 21, hold it in its lowermost position for a time, and then return it to its uppermost position, the brake shoe 53 preventing over-running of the gear

37. A three-armed pawl lever 60, pivoted at 61 on the standard 16, is adapted to engage and disengage the gear 36, said pawl lever being under the control of a pull spring 62 opposed by cams 63, 64 formed on the gear 37 and adapted to engage the actuating arm of said pawl-lever. The pawl lever is thus adapted to hold the pitman 30 accurately in its uppermost and lowermost positions and to assure the proper remeshing of the gears 36, 37.

The slide 21 is formed at its rear with vertically spaced-apart webs 64, 65, formed respectively with vertically aligned guide apertures in which is slidably mounted a bar 66 urged downward by a compression spring 67 encircling the bar and interposed between the upper web 65 and a collar 68 secured upon the bar and adapted to abut the lower web 64 to limit the bar's downward movement with relation to the slide. The lower end of said bar projects below the lower web 64 and is adapted to be engaged by the upper end of the pitman 30 to raise the bar with relation to the slide in the take-up of the pitman's lost motion with relation to the slide in the upper portion of the pitman's range of movement, said bar being adapted to be slid downward with relation to the slide, by the spring 67, as soon as the pitman again begins to descend.

The counterweights 29, when used, are preferably adapted to be stopped by the pads 29^c before the slide 21 abuts the stop collars 24, to avoid jar, the spring 67 being sufficiently strong to complete the upward movement of the slide. While the counterweights preferably are used, to avoid non-uniform power requirement, my invention is not limited thereto.

Secured upon the upper end of the bar 66 is an arm 69 formed at one end as a clamp to fit the bar 66 and provided with a screw having a handle 70 for adjustably clamping it upon the bar. At an intermediate part 71 the arm 69 is formed to fit between vertical guides 72, 72 formed on the slide 21, for sliding movement of the arm 69 in the take-up of lost motion between the pitman 30 and the slide 21.

To the grooved lower face of the outer end of the arm 69 is adjustably secured, by a thumb-screw 73, mounted in a slot 73^a formed in said arm, (Fig. 3), a toe-rest 74 formed, as shown, to embrace the toe of the last, 11. For holding the last up against said toe-rest a pair of bars 75, 75 are pivoted upon a pin 82 mounted in the arm 69 and extend downwardly from the arm and are connected near their lower ends by a stop member 76 for sleeves 77, 77 slidably mounted upon the lower ends of said bars respectively and having pivotally mounted between them, upon a pin 78, (Fig. 1), a plate 79, from the front face of which projects a

pin 80 adapted to enter a hole in the cone of the last to hold the latter against the torest 74 under the force of pull-springs 81, 81 connecting projecting ends of the plate's pivot pin 78 with the respective arms 22 of the slide 21 at positions nearer the rear of the machine than the pivot pin 82 of the bars 75, so as to urge said bars about their pivots, toward the slide 21, as well as to urge the sleeves 77 upward on said bars. Screwed into the rear face of the plate 79 is a stud 79^a adapted to abut the vertical front face of the slide 21 to position the plate 79, and a plate 83 of appropriate thickness is detachably secured to the front face of the plate 79, by studs 83^a in slots 83^b formed in the plate 79 (Fig. 3), to position the last. Plates 83 of different thickness may be used for lasts of different sizes.

20 *Heel-piece manipulating devices.*

The slide 21 is integrally formed at its lower end with a forwardly projecting portion 84 formed with a large opening 85 to permit the passage of a stock-pressing device hereinafter described, and hinged to the forward edge of said portion 84 is a drop-shelf 86 adapted to support the middle portion of the heel piece when held in horizontal position, said drop-shelf being adapted to be held in horizontal position by a push-link 87 connecting an ear 88, formed on the under side of said drop-shelf, with a cam lever 89 (see Fig. 7) pivoted to an ear 90 formed on the lower face of the slide 21, said cam-arm being adapted to raise the drop-shelf, under the action of a cam roller 91^a mounted upon the projecting end of the pitman's cross-pin 31, as the pitman 30 moves upward with relation to the slide 21, and to permit the shelf to drop in the reverse movement, a pull spring 91 being interposed operatively between the ear 90 formed on the slide 21 and the ear 88 formed on the drop-shelf 86 to assure the dropping of the shelf.

The cam-lever 89 is formed with a cam face 89^a and with a slot 92 in which is mounted a slide-block secured by rivets 93, 93 between rectangular plates, the nearer one of which is shown at 94, said plates being on opposite faces of said lever, with their left-hand edges flush with that of the lever, and one of said plates is connected by a pull spring 95 with the pivot pin at the outer end of the lever 89. Said plates are thus adapted to be held in their lowermost position with their vertical left hand edges constituting in effect a continuation of the vertical left-hand edge of the cam lever, so as to support the drop-shelf in horizontal position as the cam roller 91^a moves downward to the lower extremity of said plates, and then to permit the drop-shelf to fall suddenly. In the return movement of the cam roller 91^a, however, the plates 94 are adapted

to be lifted by the roller, against the force of the spring 95, to permit the roller 91^a, acting against the sloping cam face 89^a of the cam lever 89, to lift the drop-shelf back to horizontal position, the plates snapping back to their lower position as soon as the cam roller passes from their bottom edge faces and the face 89^a of the cam lever.

For holding the end portions of the heel piece 10 and applying them to the last, a pair of two-armed stock-pulling levers 96, 96 are pivoted at 97, 97 upon respective brackets formed upon the inner faces of the standards 15, 16. The downwardly extending arms of said levers are connected by a pull spring 98, and the upwardly extending arm of each lever, provided with stock-gripping means about to be described, is connected by a pull spring 99 with a cross-brace 100 connecting a pair of rods 101, 101, which project downward from the slide 21, the anchorage points of the springs 99 being such that when the slide 21 is in its uppermost position, as in Fig. 6, the springs 99 will be relaxed, so that the upper arms of the levers 96 will be held widely spaced apart by the lower spring 98, the middle portion of the latter being adapted to catch upon a dog 98^a projecting from a cross-bar 116 mounted upon the rods 101, as shown in Fig. 6, when the slide 21 rises. The arrangement as described is such that as the slide 21 approaches its lowermost position, as in Fig. 8, the pull of the springs 99 and of the heel piece 10 will cause an elongation of the spring 98 and swing the upper arms of the levers toward each other, to apply the heel piece to the sides of the last, the dog 98^a at this time, as it moves downward with the slide 21, permitting the spring 98 to straighten and thus relax, so as not to oppose so strongly the pull of the springs 99.

The upper end of each stock-pulling lever 96 is formed with a flat stock-receiving head 102 on which is journaled, at its inner edge, a stock-pressing roller 103 having its periphery flush with and in effect constituting a continuation of its stock-receiving face, one of the journals of the roller projecting beyond its bearing, as shown clearly in Fig. 5, and being adapted to be engaged, in the upward movement of the slide 21, by a cam 104, for suitably spacing apart the heads 102 to receive the next heel piece 10. Each of the cams 104 is formed on a lever 105 secured upon a rock-shaft 106 mounted in brackets formed on the rear of the slide 21, and provided with a rock-lever 107, Fig. 7, adapted to be engaged by a cam roller mounted back of the similar cam roller 91^a upon the projecting portion of the cross-pin 31 of the pitman 30, to lift the levers 105 with relation to the slide 21 during the take up of lost motion in the last part of the pitman's ascending stroke, and to permit the levers 105

to drop with relation to the slide during the first part of the pitman's descending stroke.

For clamping the ends of the heel piece 10 against the heads 102 of the levers 96, a clamping jaw 108 is hinged upon each of the heads at 109, provided with a hinge-spring 110 urging it toward clamping position, and formed at one end with a lever 111 adapted to be engaged by a dog 112 formed on the adjacent lever 105 to lift the clamping jaw 108 from the head 102, to permit the latter to receive the heel piece 10, when the slide 21 has arrived in its uppermost position, the levers 105 being adapted, in their downward movement by gravity in the first part of the descending stroke of the pitman 30, to permit the hinge-springs 110 to close the clamping jaws 108 upon the heel piece before the drop-shelf 86 is lowered. The heads 102 may each be provided with gauge markings 113, 113 upon gauge projections 113^a, 113^a to facilitate the positioning of the heel piece, and each of them is preferably formed, adjacent the roller 103, with a groove 102^a (Fig. 5) adapted to mate with a rounded rib 108^a formed on the jaw 108, to provide a strong, sliding grip upon the heel piece. The front journal brackets, 130^a, of the rollers 103 are adapted to serve as gauges for the heel piece at the front side of the latter. (See Fig. 5.)

The devices as described are adapted to receive the heel piece 10, clamp its ends and pull them around the heel of the last, and press them against the latter, the slide 21, with the last thereon, then stopping in a determinate position.

A device is provided for applying rolling pressure to the heel piece progressively from near the sole toward the shank of the last as the latter approaches its lowermost position. Said device comprises a T-shaped bar 114 pivoted at 115 (Fig. 9) upon a cross-bar 116, above mentioned, which is slidably mounted upon the rods 101 which project downwardly from the slide 21. Said cross-bar 116 is urged downwardly on said bars, toward stop-collars 117, 117 secured thereon, by pull strings 118 connecting said cross-bar with the lower ends of said rods. A pull spring 119 connecting an intermediate part of the T-shaped bar 114 with the cross-bar 116 is adapted to urge said bar 114, with a light force, toward the front of the machine, about its pivot 115. Pivoted upon each end of the T-head of the bar 114 is a curved arm 120, (see Figs. 6 and 8), the upper ends of the two arms 120 being connected by a flexible U-shaped axle member 121, (Fig. 9) upon which is rotatably mounted a helical spring 122 and a rubber sleeve 123 embracing said spring, the sleeve and spring being adapted to rotate, upon the curved axle member, so as to roll upon the

heel piece 10, from adjacent the sole toward the shank of the last. The T-shaped bar 114 is so formed with an angle and its pivot 115 is so positioned with relation to the last as to result in such rolling movement of the structure, toward the shank of the last, as the last is forced downward against it, the bar 114 turning about its pivot 115 under the crowding force of the work against the sleeve 123, which overcomes the force of the spring 119, the cross-bar 116 being adapted to be stopped in its downward movement by a dog 124 secured upon a fixed shaft 125 connecting the brackets 18, and the roller structure being adapted to be projected through the opening 85 of the projection 84 of the slide 21 as the slide and the last continue to move downward after the cross-bar 116 has been stopped by said dog. The arms 120 are adapted normally to rest against the walls of the opening 85 in the projection 84 of the slide 21, under the spring action of the axle member 121, but to swing toward each other under the force of the last against the flexible roller structure, to bring the legs 90 of the latter against the work, and thus to conform the flexible roller structure to the contour of the work. The front, bar portion of the projection 84, abutted by the arms 120, is adapted to serve as a stop for the bar 95 114, in opposition to the spring 119.

Sole margin folding and pressing devices.

The mechanism for folding and pressing the margin of the heel piece onto the sole 100 face of the last comprises an arch 126 (Figs. 1 and 9) secured to, and spanning the space between, the standards 15, 16, said arch being adapted to be secured at different elevations and at different angles, for different sizes or types of lasts, by bolts 127 mounted in vertical slots 128 (Fig. 2) formed in said standards. Secured to the under face of said arch is a member 129 formed with a central guide-sleeve portion 130 for the stem of a headed plunger 131, preferably having a rubber facing 131^a, and at the end of said guide-sleeve portion which is nearest the work said member 129 is formed with a portion 132 having a periphery shaped like that of the heel of the shoe, but larger, and about the curved portion of said periphery is interrupted at intervals by slots such as the one shown at 133 in Fig. 9. In each of said slots is adjustably mounted a slide 133^a, to which is pivoted a bell-crank lever 134 having a long arm extending toward the work and having pivoted to its extremity at 135^a a pair of roughly triangular roller-carrying plates, extending back along the arm of the bell-crank lever, the nearer plate of one pair being shown at 135 in Figs. 3 and 9. The outermost corners of each pair of plates are connected with the short arm of the bell-crank 130 115 120 125 130

lever 134 by a pull-spring 136 adapted to urge the plates about their pivots 135^a toward the work. A stop-pin 137 connects the plates and is adapted to abut the long 5 arm of the bell-crank lever to limit such movement. The plates are formed with parallel, finger-like extensions at their inner corners, remote from their pivots, and between each pair of said extensions is journaled 10 a roller 138, the roller-supporting mechanism just described being such that, with the long arm of each bell-crank lever in its position farthest from the work, as in Fig. 3, the series of rollers, in opened-out, U-like arrangement, will be adapted to receive the heel of the last between them, and then, as the long arms of the bell-crank levers are swung toward the work, to press the heel piece yieldingly against the last, 15 20 the rollers running thereon toward the sole of the last, as their springs 136 permit the plates 135 to turn about their pivots 135^a, until the rollers pass the junction of the side face with the sole face of the last, at 25 which time the springs 136 cause them to roll onto the sole face of the last, folding over the margin of the heel piece and pressing it against the sole face under the force of said springs, as in Fig. 9.

30 For so swinging inward the long arms of the bell-crank levers, and then to return them outward to clear the sole face of the last for the action of the plunger 131, the short arms of the bell-crank levers are connected by respective clevis-bolts 139 with a slide 140, of appropriate U-form as to its periphery, said slide being mounted upon the guide-sleeve portion 130 of the member 129. The slide 140 is pivoted between two 35 parallel, upwardly-extending arms 141, 141 of a broad lever fulcrumed on a shaft 142 rotatably mounted in the standards 15, 16, said lever having a downwardly extending arm 143 provided at its lower end with a cam roller 144 mounted in a cam groove 145 formed in the cam drum 39.

40 For actuating the plunger 131 to press the sole margin of the heel piece strongly against the last after it has been folded over, as described, by the rollers 138, the outer end of the stem of said plunger, projecting from its guide-sleeve 130, has pivoted thereto by a clevis-pin 146 a yoke 147, the ends of the latter being pivoted respectively to 45 the upper ends of two parallel lever-arms 148, 149 secured to the shaft 142, the lever-arm 149 being formed integrally with a downwardly extending arm 150 having its lower end connected by a piston-rod 151 with a piston mounted in a one way, quick-acting cylinder 152 secured to the frame of the machine, said cylinder being adapted to 50 actuate the plunger 131 as a hammer, so as to provide a very effective compacting of 55 the folded margin of the heel piece against the insole of the shoe. Said piston is adapted to be charged and exhausted through a pipe 153 provided with a three-way valve 154 having an exhaust pipe 155, the control lever, 156, of said valve being normally held in cylinder-exhausting position by a pull spring 157 connecting it with a part of the machine frame, and said control lever is adapted to be moved into cylinder-charging position, momentarily during each 70 cycle of operation, by a push-link 158 connecting it with one arm of a cam lever 159, the other arm of said lever being adapted to be engaged by a cam 160 on the cam drum 39. A pull spring 161 (Fig. 3) connects the lever 150 with the base bracket of the cylinder 152, for effecting the reverse movement of the piston when the cylinder is discharged, and so withdrawing the plunger 131 from the work.

85

Operation.

90 In the operation of the machine, the various parts thereof being in starting position as in Figs. 1, 2 and 3, and the shaft 46 being continuously driven, the heel piece 10 is manually placed upon its support comprising the projection 84 of the slide 21, the drop-shelf 110 and the heads 102 of the levers 96, and the last 11, having inner shoe parts such as the lining 12 and insole 13 thereon, is manually mounted upon the pin 80 and permitted to be held up against the toe-rest 74 by the springs 81.

95 The operator then depresses the foot lever 100 50, thereby throwing in the clutch 44, 45, the latter being automatically held in engagement by the latch 55 during one revolution of the shaft 38 and cam drum 39 thereon, and then disengaged by the action of the 105 dog 59 on said cam drum.

110 During such single revolution of the shaft 38 the crank 34 is driven in two successive half revolutions, timed by the action of the mutilated gears 36, 37. In the first part of the downward, first half-revolution of said crank, while the slide is held in its uppermost position by the spring 67 and counterweights 29, the lost motion between the slide 21 and the pitman 30 is taken up, permitting the spring 67 to extend itself and force the last downward onto the heel piece, 10, engaging the latter where it rests upon the projection 84 of the slide 21, the toe-rest arm 69 preferably being secured in such position upon the bar 66, for the particular size of shoe, that the stop-collar 68 will prevent excessive pressure of the work against said projection 84. Such take-up of lost motion permits the jaws 108 to close upon the heel piece as the roller on the pin 31 permits the levers 107 and consequently the levers 105 to fall, and also permits the drop-shelf 86 to fall away from the heel piece as the roller 91^a on said pin passes from the vertical edges 115 120 125 130

of the plates 94 and thus permits the spring 91 (see Fig. 7) to contract.

Further downward movement of the crank 34 then lowers the entire structure carried by 5 the slide 21, the heel piece being folded about the heel of the last by the action of the levers 96 and pressed against the last by the rollers 103.

Near the end of this downward movement 10 the last encounters the rolling device 121, 122, 123, as the supporting cross-bar, 116, of the latter, is stopped by the dog 124, said rolling device then being caused to roll, on its curved axle member, toward the shank of 15 the last, against the force of the spring 119, by the pressure of the last against said device, to compact the heel piece against the last.

When the slide 21 is stopped in its lowermost position, the rollers 138 are closed in and then withdrawn outwardly again by the action of the lever 143 as above described, to fold over the sole margin of the heel piece, and immediately thereafter the plunger 131 20 is actuated and withdrawn by the action of the lever 150 as above described, to compact said margin against the last, the slides 21 remaining in its lowermost position for these operations while the gear 37 is out of mesh 25 with the gear 36.

In the second or upward half of the revolution of the crank 34 the springs 118, 119 cause the heel rolling device 121, 122, 123 to withdraw downward and forward with relation to the slide 21 as the slide rises from the dog 124, and as the slide is stopped by the collars 24 in its uppermost position and the lost motion of the pitman is taken up the last is lifted with relation to the slide, 30 against the force of the spring 67. At the same time the cross-pin 31 of the pitman causes the drop-shelf 86 to be raised and the levers 105 to rise, to open the gripper jaws 108, and by contact of their cams 104 with 35 the journals of the rollers 103, to position the heads 102 to receive the next heel piece. The finished work is then removed from the machine and the operation as described is repeated.

40 In adjusting the last holding devices for lasts of a new size, the slide 21 is raised to the top of its stroke, a plate 83 of appropriate thickness is mounted upon the plate 79, and the new last is interposed between the pin 80, and the toe rest 74. The toe-rest arm 69 is then loosened on the bar 66, permitting the last to rest lightly upon a heel piece 10 supported on the projection 84 of the slide 21. The machine is then driven 45 until the lost motion of the pitman is taken up, permitting the spring 67 to force the stop-collar 68 against the lower web, 64, the bar 66 sliding in the clamping portion of the toe-rest arm 69. The clamp is then re-tightened, by means of the handle 70, so that 50

successive lasts of the same size will take only a part of the force of the spring 67 as they are brought against the projection 84 in the take-up of lost motion.

Adjustment of the last support to determine the width of heel-piece margin to be folded over onto the sole face of the last is had by adjustment of the screw-stud 79^a, and adjustment of the angle of the last, to assure that the plunger 131 will press the folded margin as effectively adjacent the instep as it does at the rear of the heel, is had by setting the toe-rest 74 at different positions on the arm 69, by means of the thumb-screw 73 in the slot 73^a.

The sole-margin rolling devices do not ordinarily require special adjustment for different sized lasts, but to assure their proper cooperation with each other they may be individually adjusted by adjusting the slides 133^a, upon which they are fulcrumed, in the slots 133.

My invention is susceptible of various modifications within its scope and I do not wholly limit my claims to the specific construction shown or the exact procedure described.

I claim:

1. The method of making footwear which comprises bringing a piece of sheet stock and a last together, by determinate relative movement from determinate, isolated positions, progressively applying the stock to the last by giving it off against the same by slippage of the stock from gripping members moved, relatively, along the face of the last, and progressively pressing the stock against the last concurrently with its progressive application thereto.

2. The method of applying a heel piece to a last which comprises bringing the heel piece and the last together by determinate relative movement from determinate, isolated positions, applying the heel piece to the last progressively in opposite directions from the middle of the heel by determinate relative movement of the two, and folding inward the sole margin of the heel piece toward the sole face of the last simultaneously at substantially all points throughout its length.

3. The method of applying an upper shoe part to a last which comprises sticking the shoe part to the last with a margin thereof extending past the sole face of the last, supporting the last in a determinate position with the shoe part thus mounted thereon, folding inward the said margin toward the sole face of the last while the latter is supported in said position, and, while the last remains in said position, pressing against the last simultaneously the entire area of the folded margin by presenting pressing means thereto by movement substantially normal to the sole of the last.

4. Apparatus for making footwear, said apparatus comprising means for bringing a piece of shoe stock and a last together by determinate relative movement from isolated positions and progressively applying the stock to the last, said means comprising a gripper having movement along the face of the last and adapted to give off the stock to the last by slippage of the stock from between its gripping members and locally acting means associated with the gripper and adapted therewith relatively to travel over the face of the work for pressing the stock against the last locally and by progression 10 over the work as the stock is so given off.

5. Apparatus for making footwear, said apparatus comprising means for supporting a last, gripper means relatively movable along the face of the last and adapted to give off stock under tension to the last, and a roller adapted to be moved along with said gripper means to press the stock against the last, the last supporting means and the gripper means being mounted for relative movement such as to bring the last and stock together by determinate movement from determinate, isolated positions.

6. Apparatus for applying a heel piece to a last, said apparatus comprising means adapted to receive and hold the heel piece in a determinate position, means adapted to receive and hold a last in determinate position isolated from that of the heel piece, and means for effecting such relative movement 30 of the two as to cause the heel piece first to contact the last at the middle line of the latter's heel portion and then to be applied to the last progressively in opposite directions from said middle line.

7. Apparatus for applying a heel piece to a last, said apparatus comprising means adapted to receive and hold the heel piece in a determinate position, means adapted to receive and hold a last in determinate position 45 isolated from that of the heel piece, means for effecting such relative movement of the two as to cause the heel piece first to contact the last at the middle line of the latter's heel portion and then to be applied to the last progressively in opposite directions from said middle line, and roller means adapted to run, upon the shank portion of the heel piece, toward the cone of the last.

8. Apparatus for applying a heel piece to a last, said apparatus comprising means adapted to receive and hold the heel piece in a determinate position, means adapted to receive and hold a last in determinate position isolated from that of the heel piece, means 50 for effecting such relative movement of the two as to cause the heel piece first to contact the last at the middle line of the latter's heel portion and then to be applied to the last progressively in opposite directions from 55 said middle line, and means for folding in-

ward the sole margin of the heel piece, toward the sole face of the last.

9. Apparatus for making footwear, said apparatus comprising a pair of holding devices adapted to anchor the ends of a piece 70 of shoe stock to hold the same in position to receive a last, and to be moved toward the last as the latter passes between them, to apply the end portions of the piece to the last and press them thereagainst, and means 75 for relatively so moving the last and holding devices as to cause the piece thus to be applied thereto by said holding devices.

10. Apparatus for making footwear, said apparatus comprising a pair of holding devices adapted to anchor the ends of a heel piece to hold the same in position to receive a last, and to apply the end portions of the heel piece to the last, means for relatively so moving the last as to cause the heel piece 80 thus to be applied thereto by said holding means and for holding the last in a determinate position at the end of such heel-piece-applying movement, means for folding inward the sole margin of the heel piece while 85 the last is held in such determinate position and driving means common to all of the aforesaid means and adapted to effect their operation in timed relation.

11. Apparatus for making footwear, said 95 apparatus comprising a pair of holding devices adapted to anchor the ends of a heel piece to hold the same in position to receive a last, and to apply the end portions of the heel piece to the last, means for relatively so moving the last as to cause the heel piece thus to be applied thereto by said holding means and for holding the last in a determinate position at the end of such heel-piece-applying movement, means for folding inward the sole margin of the heel piece while 100 the last is held in such determinate position, and additional means for pressing the folded margin against the last.

12. Apparatus for making footwear, said 110 apparatus comprising a pair of holding devices adapted to anchor the ends of a heel piece to hold the same in position to receive a last, and to apply the end portions of the heel piece to the last, means for relatively so moving the last as to cause the heel piece thus to be applied thereto by said holding means and for holding the last in a determinate position at the end of such heel-piece-applying movement, means for folding inward the sole margin of the heel piece while 115 the last is held in such determinate position, additional means for pressing the folded margin against the last, and driving means common to all of the aforesaid means and 120 adapted to effect their operation in timed relation.

13. Apparatus for making footwear, said apparatus comprising a toe-support adapted 125 to straddle the toe end of a last from the 130

front of the toe of the last, means adapted yieldingly to engage the cone of the last to hold it against said toe support, and means for presenting and applying a piece of shoe stock to the last while it is so held.

14. Apparatus for making footwear, said apparatus comprising a pair of stock-holding devices spaced apart to permit the passage of a last between them and adapted to anchor the end portions of a heel piece to receive a last, last-holding means comprising a toe-support and means engaging the cone of the last for holding it against said toe-support, and means for relatively so moving said last-holding means as to cause the heel portion of the last to engage the heel piece and flex the latter into conformity with said heel portion of the last.

15. Apparatus for making footwear, said apparatus comprising a pair of stock-holding devices spaced apart to permit the passage of a last between them and adapted to anchor opposite margins of a piece of shoe stock and to be moved toward each other to apply the stock progressively to a last moved between them, means for relatively so moving a last between them as to cause it to engage the piece of stock and flex the latter into conformity with the last, and yielding means adapted to urge said stock-holding devices away from each other during an early part of the last's movement between them and to urge them toward each other in a later part of said movement.

16. Apparatus as defined in claim 15 in which each of the stock holding devices is adapted to give off the stock to the last and progressively to press it against the last as it is so given off.

17. Apparatus for making footwear, said apparatus comprising a pair of stock-holding devices spaced apart to permit the passage of a last between them and adapted to anchor opposite margins of a piece of shoe stock and to be moved toward each other to apply the stock progressively to a last moved between them, means for relatively so moving a last between them as to cause it to engage the piece of stock and flex the latter into conformity with the last, yielding means adapted to urge said stock-holding devices away from each other in an early part of the last's movement between them and to urge them toward each other in a later part of said movement, and positive means for positioning said stock-holding devices to receive the piece of shoe stock.

18. Apparatus for making footwear, said apparatus comprising a movable last-carrier adapted to support a last with the sole face thereof substantially parallel with the line of movement of the last-carrier and with its cone supported by said carrier against force directed normally against the sole face of the last, means for holding a piece of upper shoe

stock in position to be received by and wrapped about the last in such movement thereof, and power-actuated plunger means for pressing stock against the sole face of the last while the latter is so supported.

19. Apparatus for making footwear, said apparatus comprising a movable last-carrier adapted to support a last with the sole face thereof substantially parallel with the line of movement of the last-carrier and with its cone supported by said carrier against force directed normally against the sole face of the last, means for applying stock to the last and folding the sole margin of the stock inwardly toward the sole face of the last while the latter is supported by said last-carrier, and power-actuated plunger means for pressing stock against the sole face of the last while the latter is so supported.

20. Apparatus for making footwear, said apparatus comprising a pivoted arm, yielding means urging said arm about its pivot, a stop for said arm opposing said yielding means, a flexible roller device of U-formation supported by its ends on said arm, and means for presenting a last to said roller-device in such position and from such direction as to cause the roller-device to embrace the last and to roll thereon against the force of said yielding means.

21. Apparatus for making footwear, said apparatus comprising a pivoted arm, yielding means urging said arm about its pivot, a stop for said arm opposing said yielding means, a flexible roller device of U-formation supported by its ends on said arm, and means for presenting a last to said roller-device in such position and from such direction as to cause the roller-device to embrace the heel portion of the last and to roll thereon toward the shank of the last, against the force of said yielding means.

22. Apparatus for applying a heel-piece to a last, said apparatus comprising means for first applying the heel piece to the last at the middle line of the latter's heel portion, means for pressing the end portions of the heel piece against the last, progressively toward the toe of the last, and means for pressing the shank portion of the heel piece against the last, progressively toward the shank of the last.

23. Apparatus for making footwear, said apparatus comprising a member adapted to support the middle portion of a heel piece, means for yieldingly holding a last with the middle part of its heel portion pressing the heel piece against said member, and means for pressing the heel piece against the last progressively in three directions from the portion held between said member and the last.

24. Apparatus for making footwear, said apparatus comprising a device for gripping a margin of a piece of shoe stock, a last-

support, lost-motion means for moving one of the same with relation to the other to apply to a last on said last-support, a piece of shoe stock held by said gripping device, and means actuated by the take-up of the lost motion of said lost motion means for actuating said gripping device.

25. Apparatus for making footwear, said apparatus comprising a device for gripping 10 a margin of a piece of shoe stock, a last-support, lost-motion means for moving one of the same with relation to the other to apply to a last on said last-support, a piece of shoe stock held by said gripping device, 15 and means actuated by the take-up of the lost motion of said lost motion means for positioning said gripping device with relation to said last-support.

26. Apparatus for building footwear, said 20 apparatus comprising a pair of gripping devices adapted to anchor opposite margins of a piece of shoe-stock, a stock-support for the intermediate portion of said piece, a last-support adapted to carry a last into association with the piece of stock as the latter is held by said gripping devices, lost-motion means for moving said last-support, and means actuated by the take-up of the lost motion of said lost-motion means for 30 closing said gripping devices on the stock and withdrawing said stock-support from said piece in timed relation.

27. Apparatus for making footwear, said 35 apparatus comprising a last support for holding a last with an upper shoe part thereon having a margin projecting past the sole face of the last, a roller, and means for passing said roller from a side face onto the sole face of the last to fold said projecting 40 margin onto said sole face, said means comprising a roller-support relatively movable to carry the roller past the junction of the side face and the sole face of the last, and a single spring adapted to urge said roller 45 against the work both before and after it passes said junction in such movement.

28. Apparatus for making footwear, said apparatus comprising a last-support for holding a last in determinate position with an upper shoe part thereon having a margin 50 projecting past its sole face, a set of rollers spaced about a portion of the sole face of the last, and means for closing in said set of rollers against the side faces of the last and rolling them from the side faces onto 55 the sole face of the last to fold inward the projecting margin of the shoe part, said means being adapted to actuate and to withdraw the rollers, leaving the sole face of the last unobstructed, while the last remains 60 in said determinate position.

29. In combination with apparatus as defined in claim 28, a plunger device for pressing the folded margin of the shoe part against the sole face of the last while the 65 last remains in said determinate position.

30. Apparatus for making footwear, said apparatus comprising a last-support for holding a last in determinate position with an upper shoe part thereon having a margin 70 projecting past its sole face, a set of rollers spaced about a portion of the sole face of the last, and means for closing in said set of rollers against the side faces of the last and rolling them from the side faces onto 75 the sole face of the last to fold inward the projecting margin of the shoe part, said means comprising a set of supporting members spaced about the last and adapted to be closed in toward the latter by movement 80 substantially parallel with the sole face of the last, a journal arm for each roller, each journal arm being pivoted on its supporting member at a point opposite the side face of the last and extending from its pivot toward the sole face of the last, and yielding means urging each arm about its pivot toward the last.

In witness whereof I have hereunto set my hand this 4th day of September, 1924.

FRANK J. MACDONALD.
